(57) CLAIM

The ornamental design for a scripture wallpaper, as shown and described.

DESCRIPTION

The sole FIGURE is a top plan view showing my new design.

In the drawing the broken lines depict the boundaries of the claimed design and indicate that the design contains indeterminately in one or more directions.

The broken lines form no part of the claim.

The sides and rear surfaces of the wallpaper form no part of the claimed design.

1 Claim, 1 Drawing Sheet

And they sing the song of Moses the Servant of God, and the song of the Lamb, saying Great and Marvelous are your works, Lord God Almighty; Just and True are Thy ways, thou King of saints.

Rev. 15:3

Now the God of Peace, that brought again from the dead our Lord Jesus, that great Shepherd of the sheep through the blood of the everlasting covenant. Heb. 13:9

And Jesus, when he was baptized, went up straightway out of the water: and lo, the heavens were opened unto him, and he saw the spirit of God descending like a dove, and lighting upon him. Matt. 3:16

In the middle of its side of the river, was bare twelve manner her fruit every month: tree were for healing street and on either the tree of life, which of fruits, and yielded and the leaves of the of the Nations. Rev. 22:2

For the commandment is a lamp, and the law is light and reproof of instruction are the way of life. Proverbs 6:23
